(57) **CLAIM**

The ornamental design for a string lamp, as shown and described.

DESCRIPTION

FIG. 1 is a front, left, and top perspective view of a string lamp, showing my design.

FIG. 2 is an enlarged rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of a lamp holder labeled 9 in FIG. 2.

The broken lines shown in the drawings are included for the purpose of illustrating portions of the string lamp that form no part of the claimed design. A symbolic break, shown in broken line, appears in the length of the string lamp. The break line, as well as the appearance of any portion of the string lamp beyond the break line, forms no part of the claimed design. The broken lines of alternating length in FIGS. 2 and 9 are for purpose of illustrating the boundaries of the enlarged fragments shown in FIGS. 9 and form no part of the claimed design.
